UNITED STATES PATENT OFFICE.

ELIZABETH C. SCANLAN, OF NEWARK, NEW JERSEY.

HAT-FASTENING DEVICE.

No. 895,500.

Specification of Letters Patent.

Patented Aug. 11, 1908.

Application filed September 27, 1907. Serial No. 394,867.

To all whom it may concern:

Be it known that I, ELIZABETH C. SCANLAN, residing in the city of Newark, in the county of Essex and State of New Jersey, have invented certain new and useful Improvements in Hat-Fastening Devices; and I do hereby declare the following to be a full, clear, and exact description of the same, such as will enable others skilled in the art to which it pertains to make, construct, and use the same.

My invention relates to means for fastening ladies' hats to the head of the wearer in such a manner, that the hat is perfectly secure against accidental displacement, or removal, and consists in an attachment secured to the inner side of the hat, in such a way as to project below the hat body and lie against the hair of the wearer, so as to permit a hairpin or other fastening member to be inserted or threaded through apertures in the device and engage a wisp or lock of hair of the wearer.

The present custom of attaching a lady's hat to the head, consists almost universally in inserting long metal hat pins through the side or body of the hat, and engage the hair at the top of the head. The use of such pins results frequently in the injury of the hat and its trimmings, and to the hair, besides affording only an insecure fastening means.

In carrying out my invention, I make use of the device hereinafter described and illustrated in the accompanying drawings, in which

Figure 1 is a side elevation of the device illustrating the ordinary bone hairpin inserted through apertures in the device, and engaging a wisp or lock of hair. Fig. 2 is a side elevation of the same, illustrating the method of threading the hairpin through the apertures in the device. Fig. 3 is a perspective view of the device, illustrating a modified form of fastening member to be used in connection therewith. Fig. 4 illustrates the method of using the device for securing a lady's hat in position. Fig. 5 illustrates an inverted perspective view of a hat, illustrating three of the fastening devices in position. Fig. 6 illustrates a modification, in which the fastening device is secured to or forms a part of one of the hat wires forming the frame of the hat, and Fig. 7 illustrates a further modification of Fig. 6, showing the method of twisting the wires together in such a way that the loops are tied together.

Similar letters of reference refer to like parts throughout the specification and drawings.

In carrying out my invention, I use a piece 60 of flexible material or fabric 1 formed substantially as illustrated in Fig. 1. It consists of a flat piece of material having the upwardly projecting tongues 2, provided with notches 3 in their edges, and perforations 4 65 in their face, such notches and perforations being for the purpose of sewing or securing the same within the body or crown of the hat. The main body of the fastening device projects below the body of the hat, as illustrated 70 in Fig. 4, and is provided with the vertically elongated apertures 5, spaced for a considerable distance from each other. Through these apertures, the ordinary bone or shell hairpin 6 is inserted in such a way as to catch 75 a lock of the hair of the wearer, and thus securely fasten the device, and with it, the hat to the head of the wearer. The hairpin when in position, lies substantially in a horizontal position, and owing to the elasticity of the 80 body of the fastening device 1, the hairpin 6 is quite firmly gripped in position in such a way that it cannot fall out, or be accidentally displaced.

In the modification illustrated in Fig. 3, I 85 may provide the fastening member itself with the offset bends 7, located in such a position, that when the member is inserted through the apertures 5, such bends will engage the margins of the apertures and thus 90 securely lock the member against accidental displacement. When in position, the member being somewhat elastic, these offset bends 7 will project beyond the margin of the aperture, as clearly shown in said figure. 95

In Fig. 6, I have shown a modification in which the body piece 8 is one of the flexible wires which forms a part of the hat frame, preferably, the part which encircles the crown of the head when in use. In this case, 100 the body piece and the apertured loops 9 are integral and continuous, the loops 9 projecting below what would be the body of the hat in substantially the same position as indicated in Fig. 5, the loops 9 serving to receive 105 the other fastening member 6. In this case, the same kind of a fastening member as illustrated in Fig. 3, can be used, that is, with the projections 7 thereon for locking the fastening member 6 within the loops or apertures 9. 110 If desired, the loops 9 may be integral with any other member of the hat frame, it being

understood that the member 8 is shown merely for the purpose of illustrating a method of securing the fastening member to the hat body.

- 5 The structure illustrated in Figs. 1 to 5 inclusive, may be made of any flexible material, such as transparent celluloid, or stiff but flexible fabric, and is ordinarily made up in colors to match the hair of the wearer, while 10 the modification illustrated in Fig. 6 is made up of the usual flexible wire, of which the frames of ladies' hats are made.

In each of the modifications illustrated, the part projecting below the hat may be 15 termed a pair of loops. In the case of Figs. 1 to 5 inclusive, these loops are integrally connected together at their adjacent sides; in Fig. 6, the adjacent portions of the loops are shown as separate and distinct, while in Fig. 20 7, adjacent portions of the loop are twisted together, so as to form a structure similar to that described in Figs. 1 to 5 inclusive.

In practice, two or more of the fastening devices are secured to the interior of a hat, 25 one at each side, and if desired, one or more at the rear of the hat.

It will thus be seen that I have provided a fastening device of such a character, as to firmly secure the hat to the head of the 30 wearer, whereby, injury to the body of the hat itself is avoided, and inasmuch as the fastening member normally lies in a substantially horizontal position, the accidental displacement of the same is obviated.

35 I claim:

1. In combination with a hat, means for fastening said hat to the head of the wearer, consisting of a member secured to and projecting below the body of the hat in the form 40 of a pair of loops, and a fastening member adapted to be horizontally inserted through said loops in said first named member and engaging the hair of the wearer.

2. The combination with a hat, of a hat 45 fastening device, comprising a body piece having means thereon for fastening the same to the body of the hat, said body piece being provided with a pair of parallel vertically elongated loops, and a fastening member 50 adapted to be horizontally inserted through said loops to engage a lock of hair of the wearer.

3. The combination with a hat, of a hat

fastening device, comprising a flexible body piece secured to and projecting below the 55 body of a hat, said body piece being provided with a pair of parallel vertically elongated loops, and a fastening member adapted to be horizontally inserted through said loops to engage a lock of the hair of the 60 wearer.

4. The combination with a hat, of a hat 65 fastening device, consisting of a body piece adapted to be secured to the body of the hat, and a fastening member, said body piece being provided with a pair of vertically elongated parallel loops or slots to receive said fastening member in a horizontal position and permit the same to engage the hair of the 70 wearer.

5. The combination with the body of a hat, with a flexible body piece secured to and projecting below the body of the hat, said body piece being provided with a plurality 75 of parallel slots perpendicular to the body of the hat and a fastening member adapted to be horizontally inserted through said slots to engage the hair of the wearer.

6. The combination with a hat, of a hat 80 fastening device, comprising a body piece having means thereon for fastening the same to the body of the hat, said body piece being provided with a pair of parallel vertically elongated apertures, a fastening member 85 adapted to be inserted through said apertures to engage a lock of hair of the wearer, said fastening member having means thereon to prevent accidental disengagement from said apertures.

7. The combination with a hat, of a hat 90 fastening device, comprising a flexible body piece secured to and projecting below the body of a hat, said body piece being provided with a pair of parallel vertically elongated apertures, a fastening member inserted 95 through said apertures to engage a lock of the hair of the wearer, and projections upon said fastening member for engagement with one of said apertures to prevent accidental disengagement.

This specification signed and witnessed this 20th day of Sept 1907.

ELIZABETH C. SCANLAN.
